UNITED STATES PATENT OFFICE.

GEORGE GORDON GREEN, OF BATTELLE, ALABAMA.

HAND-POWER HAY-BALER.

1,113,000.

Specification of Letters Patent.

Patented Oct. 6, 1914.

Application filed October 21, 1913, Serial No. 796,459. Renewed August 19, 1914. Serial No. 857,610.

To all whom it may concern:

Be it known that I, GEORGE G. GREEN, a citizen of the United States, residing at Battelle, in the county of Dekalb and State of Alabama, have invented new and useful Improvements in Hand-Power Hay-Balers, of which the following is a specification.

This invention relates to baling presses and has special reference to a novel arrangement of baling chamber and door therefor.

The principal object of the invention is to improve and simplify the general construction of device of this character.

A second object of the invention is to provide a novel form of door, which, when opened, will simultaneously open the top and one side of the baling chamber.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1 is a side elevation of a baling press constructed in accordance with this invention. Fig. 2 is a rear end view of such a press, the door being shown open in dotted lines. Fig. 3 is a front elevation showing open end with follower head in position. Fig. 4 is a detail plan view of a portion of the press showing the follower head or piston.

In the embodiment of the invention herein shown there are provided suitable supports 10 which are here shown as ordinary standards but, which if desired may be replaced by wheels or other like means to enable the device to be transported from place to place. These wheels are not deemed necessary here to be shown as they form no part of the present invention and are common in devices of this character.

The press proper consists of a rectangular box having the side members 11 which are preferably three in number and spaced to provide a pair of slots 12 extending longitudinally up the side. There is also provided a bottom 13 and top 14. These parts are held together by means of straps 15. These straps are so arranged that each strap is secured to one side of the press and either the top or bottom thereof, there thus being a plurality of straps on one side which are

secured to the top while on the other side there are a plurality of straps which are secured to the bottom. These straps are formed of some rigid material so that the top and side will move in unison and be rigidly and fixedly connected. The straps on one side and the bottom are secured to the straps on the other side and the top by means of hinges 16 which are located at the lower end of the strap on the last mentioned side as can clearly be seen by reference to Figs. 1, 2 and 3.

At one end the baling chamber is closed as at 17 and on this closed end is mounted a pair of spaced brackets 18 which support a shaft 19. On this shaft 19 is a ratchet wheel 20 while pivoted to the end 17 is a retaining pawl 21. On the shaft 19 also works an operating lever 22 which has pivoted thereto an operating pawl 22'. Thus by operation of the lever 22 the ratchet 20 is caused to rotate. Secured to each end of the shaft 19 is a chain 23 and to one of the chains 23 is connected a V-shaped pair of hooks 24 while to the other chain is connected a V-shaped member 25 which has its ends bent inward through the respective slots 12 and pivotally connected as at 26 to a plunger 27. The hook 24 is so arranged that its end may pass through the slot on the side opposite the hook 25 and engage the free end of said plunger 27.

The straps which are connected to the top and one side may be preferably termed the swinging or door straps while the straps which are connected to the bottom and the other side are termed the fixed straps or stationary straps. Pivoted to these stationary straps are latches 28 which engage with the projecting ends 29 formed on the strap connected to the top when the latter is closed.

In the operation of the device the hook 24 is disengaged from the plunger 27 so that hay may be inserted in the openings of the baling press, the top and side being closed on the bottom and other side as shown in full lines in Fig. 2. This disengaged position of the hook and plunger are illustrated in Fig. 4 and after the hay has been placed in the press the plunger is swung across the baling chamber and the hook 24 engaged with the free end thereof. Then by working the handle of the lever 22 the plunger is drawn toward the closed end 17 of the

press and the bale compressed. After the bale has been fully compressed and the necessary wires applied thereto, which may be done manually, the latches are loosed and 5 the side and top swung out to the position shown in Fig. 2 for the side may be dropped entirely and rest against the legs of the standard 10. In this position the bale may be readily removed when pressure is relaxed 10 upon the plunger 27.

There has thus been provided a simple and efficient device of the kind described and of the character specified.

It will be obvious that many minor 15 changes may be made in the form and construction of this invention without departing from the material principles thereof. It is not therefore desired to confine the invention to the exact form herein shown and described, but it is wished to include all such 20 as come properly within the scope claimed.

Having thus described the invention, what is claimed as new, is:—

In a baling press, a baling chamber having slotted sides, a pawl and ratchet mechanism at one end of said chamber, a pair of flexible tension members arranged on opposite sides of said press and arranged to be wound by said mechanism, a plunger movable in said chamber, a pivoted connection 25 between one of said tension members and said plunger and extending through a slot, and a hook carried by the other member and adapted to extend through a second slot for releasable engagement with the free edge 30 of said plunger.

In testimony whereof I affix my signature in the presence of two witnesses.

GEORGE GORDON GREEN.
